UNITED STATES PATENT OFFICE.

WILFRED BARNES, OF LYNN, MASSACHUSETTS.

ELECTROLYZING APPARATUS.

SPECIFICATION forming part of Letters Patent No. 641,820, dated January 23, 1900.

Application filed January 17, 1898. Serial No. 866,845. (No model.)

To all whom it may concern:

Be it known that I, WILFRED BARNES, of Lynn, in the county of Essex and State of Massachusetts, have invented an Improvement in Electrolyzing Apparatus, of which the following is a specification.

Referring to the drawings, Figure 1 is a side elevation of the preferred form of my improved electrolyzing apparatus, and Fig. 2 is a top plan view thereof. Fig. 3 is an end view of the cell. Fig. 4 is a sectional view on line 4-4 of Fig. 2, showing the diaphragm in side elevation. Fig. 5 shows a modification wherein the cell comprises two hermetically-sealed receptacles, one within another. Fig. 6 is a cross-sectional view on line 6-6 of Fig. 7 of a modification, showing a rotary electrode. Fig. 7 shows in top plan a modification of the cell with the cover removed, one electrode being rotary and one stationary. Fig. 8 shows a modification in which the electrode is made up of a bar and attached blocks. Fig. 9 shows a modification in which the diaphragm extends but part way from the surface of the electrolyte to the bottom thereof.

The object of my invention is to produce a new process of electrolysis and an electrolyzing apparatus adapted for use on a large scale to secure the gaseous products of electrolysis by escape of the gases from the electrolyte; and my invention consists, broadly, in the combination of a hermetically-sealed electrolytic cell with a vacuum-creating device by means of which a vacuum is formed in at least one of the cell-compartments and escape of gas from the electrolyte secured.

Referring to the accompanying drawings, illustrating the principle of my invention and the best mode of applying that principle now known to me, A is the main feed or supply reservoir, provided, preferably, with a mechanical agitator a, mounted upon a shaft a', rotated through the intermeshing gears a² and a³, gear a³ being on shaft a⁴, provided with suitable driving-pulleys a⁵.

a⁶ is the feed pipe or conduit from reservoir A and is preferably provided with suitable feed-regulating valves a⁷. Feed-conduit a⁶ conveys matter to be electrolyzed from reservoir A and discharges its contents through any suitable connection into supply-conduit b of the automatic feed-regulator B. Preferably

feed-conduit a⁶ of reservoir A and the supply-conduits b of the automatic feed-regulators B are separated by intermediate reservoirs A', 55 conduit a⁸ discharging into the inlets a⁹ of reservoirs A'. Conduit a⁸ is preferably out of contact with reservoirs A'. It is to be understood that the feed of the solution through conduit a⁸ is preferably a continuous drop⁶⁰ ping from conduit a⁸ into inlets a⁹ of reservoirs A', so that the continuously-dropping solution is not an effective conductor for an electric current from electrolyzing-cell B' to conduit a⁸. If the solution should be fed as 65 a continuous column through conduit a⁸ into reservoirs A' and through conduit b, regulator B, and cell B', any electricity in conduit b would follow the continuous liquid column back into conduit a⁸ and its connected parts, 70 and this would be objectionable, because it would involve a waste of electric current. Therefore conduit a⁸ is preferably wholly disconnected from the reservoirs A'. Supply-conduit b is preferably provided with an insulating-section b' for the same reasons to prevent 75 the conduit acting as an electrical conductor and should be provided with a thermometer b² to indicate the temperature of the solution flowing to the regulator B and cell B'. 80 A supply-conduit b connects each reservoir A' with each regulator B. From each regulator B a supply or feed main b³ extends, and from it branch pipes b⁴ enter a cell-compartment, each branch having a regulating-valve 85 b⁵. A glass tube b⁶ is preferably mounted vertically between each set of upper and lower conduits b⁶ from the compartments and communicates with them in order to show the level of the electrolyte in the cell. Each tube 90 b⁶ is shown provided with valves b⁷, which are at the upper and lower ends of the glass tubes b⁶, so that in case of a break thereof the entrances to the tubes may be temporarily closed and the operation of the apparatus be continued without interruption for some little length of time until a new glass can be put back. One of each set of conduits b⁶ opens into a compartment at the upper or gas-receiving portion thereof and the other 95 opens into the compartment at the lower or electrolyte-containing portion thereof. With the upper and lower conduit b⁶ a branch pipe b⁸, open to the atmosphere at its free end,

communicates. Each branch b^7 is provided with a valve b^8 , whereby the branch is kept normally closed. By opening an upper valve b^8 gas may be drawn for testing. By opening one of the lower valves b^8 electrolyte may be drawn off for testing. The discharge end of conduit b is provided with a float-valve b^9 within the automatic feed-regulator B. Here the valve is out of contact with the gases which tend to destroy it if it were placed in a cell-compartment. The float-valve b^9 is mounted so as to close automatically when the solution reaches the solution-level of the cells and to open automatically when the solution falls below the desired level thereof. The feed-pipes b^4 from the main b^3 are normally open, but may be closed by valves b^{10} . The solution is therefore of the same level normally in the cells as in the regulators B.

As in accordance with this invention vacuums are to be created and maintained on one or both compartments of each cell above the solution-level, it is necessary that there should not be any atmospheric pressure on the solution in the feed-regulator B, for if there were it would force the solution in the regulator out into the cells and interfere with the vacuums maintained there. Hence this feed-regulator is of hermetically-closed construction and connected at its upper portion by pipe b^{10} with the vacuum-main d^{8*} , (hereinafter described,) through which and its connected devices the same vacuum is maintained in the upper portion of the regulator as in the upper portions of the cell-compartments. In this preferred construction there is one regulator B for each series of anode-compartments and one regulator for each series of cathode-compartments, each main b^3 from a regulator B being piped to a series of similar cell-compartments. Electrode b^{11} in this instance is the anode and electrode b^{12} the cathode. The porous partition B^2 separates cell B' into two compartments, one of the electrodes being in one compartment and the other electrode in the other compartment, as will be readily understood by all skilled in the art. The leads b^{13} and b^{14} from any suitable source of electricity (represented by C) connect with the electrodes b^{11} and b^{12} , passing through the packing-glands b^{15} and b^{16} on a wall of the cell. The glands are of such construction as to permit the passage of the leads without making the cell non-air-tight and so interfering with the maintenance of vacuums in the cell-compartments. The current passes through lead b^{13} and its electrically-connected anode and thence through the porous partition and electrolyte to the cathode and lead b^{14} to the generator.

As above stated, cell B' is divided into two compartments by any suitable diaphragm having porosities. Diaphragm B^2 is readily made by mounting in an opening through a board a porous block b^{17} , made out of asbestos sheets pressed together and secured in place over or in the opening. The asbestos board

does not necessarily require any preliminary preparation to prevent pulping in solution. The diaphragm or partition B^2 extends from top to bottom of cell B' , wholly separating it into two distinct compartments B^3 and B^4 . That portion of partition B^2 which is above the normal solution-level indicated by the line marked b^{19} is non-porous, the porous portion of the partition being at b^{20} . The lower margin of the partition is preferably non-porous, so as to give a firm bearing portion at its lower edge. Cell B' may be of any suitable material—such as wood, wood lined with cement, wood lined with brick, wood lined with porcelain or glass, or it can be made wholly of slate or of any other suitable material or combination of materials.

Each compartment B^3 B^4 is hermetically closed from the atmosphere in order that a partial vacuum may be maintained in each compartment above the surface of the electrolyte therein. To this end I prefer to make the cell-cover in sections b^{21} , with rubber packings b^{22} between opposed edges of the sections. A rubber packing b^{23} is interposed between the upper edges of cell B' and the bottom of the cover formed of the sections. On the exterior of the cell I mount suitable brackets b^{24} , from which swinging bolts b^{25} extend upwardly and enter slots b^{26} in the edges of the cover-forming sections. By tightening the nuts b^{27} of the bolts the rubber packings are compressed and the cell hermetically closed. This construction is effective for the purpose described and also permits the ready removal of the cover for interior inspection of the cell. The spaces in compartments B^3 B^4 above the level of the electrolyte form receivers for gases produced by the electrolysis. From the upper portion of the compartment B^3 a pipe d , preferably provided with a regulating-valve d' , leads toward a vacuum-pump D, the pipe d communicating through its branch d^2 with the vacuum-main d^3 . The cells are used in series, main d^3 being connected by a pipe d^4 to the vacuum-pump. The upper portion of compartment B^4 is connected by a pipe d^5 , provided, preferably, with a regulating-valve d^6 , with the vacuum-main d^{3*} , which communicates through vacuum-main d^7 with vacuum-pump D'. The vacuum-mains d^4 and d^7 are each provided with a suitable vacuum-relief d^8 and vacuum-gage d^9 , the construction and mode of operation of which will be readily understood by all skilled in the art. It is to be understood that in case only one cell is used the piping will be varied, and the conduits d and d^5 may lead directly (instead of through the mains d^4 and d^7) to the independent vacuum-pumps D and D', one of which establishes a vacuum in one compartment of the cell and draws off gas therefrom and the other of which establishes a vacuum in the other compartment and draws off gas therefrom. By the expression "vacuum-pump" I mean to include any suitable exhausting apparatus. Each vacuum-pump or apparatus

is provided with a discharge-conduit D^2 , which may lead to any suitable storage-receivers, where the products of electrolysis may be handled for commercial purposes.

5 The electrolyte in cells B' becomes weakened by the electrolysis and withdrawal of gases and requires renewal from time to time, and in order that the electrolysis may be kept continuous and not be interrupted by the withdrawal of the weakened electrolyte I provide means for withdrawing the weakened electrolyte from compartments B^3 and B^4 while the fresh solution is being supplied through conduits b^4 . To this end I provide

10 each compartment B^3 and B^4 of the cell with an outlet-pipe f , each provided with a suitable regulating-valve f' and preferably with an insulating-section f^2 , which lead, respectively, to auxiliary vacuum-tanks F and F' .

15 Vacuum-tank F is provided at its upper end with a pipe f^3 , from which a pipe f^4 leads to the vacuum-main d^4 , being preferably provided with regulating-valves f^5 and f^6 . The pipe f^3 may be opened to the atmosphere by opening valve f^7 , near its open free end. Vacuum-tank F' is provided near its upper end with a pipe f^8 , having a communicating pipe f^9 , preferably provided with regulating-valves f^{10} . This pipe f^9 opens into the vacuum-

20 main d^{3*} of the vacuum-pump D' , an auxiliary vacuum-main d^{3*} being interposed when the cells are used in series between the pipe f^9 and vacuum-main d^7 just as the auxiliary vacuum-main d^8 is interposed between the

25 pipe d^2 and vacuum-main d^4 . Vacuum-tanks F and F' are provided each with an outlet-pipe f^{11} , leading to a stand-pipe f^{12} and entering the stand-pipe near its bottom. From the bottom portion of the stand-pipe a pipe

30 f^{13} extends to the cylinder f^{14} of a pump whose discharge-pipe f^{15} discharges into the auxiliary supply-reservoir A^2 . The vacuum-tanks F and F' are each provided with a suitable glass f^{17} to show the depth of the solution in the tanks F and F' , for when valves f' are open the weakened electrolyte in the cell flows to the vacuum-tanks F and F' , accumulating at the bottom thereof, the same vacuum being established in the tanks F and F' that

35 there is above the electrolyte in the compartments B^3 and B^4 . The vacuum-tanks may be put into operation both at the same time or one at a time. These vacuums are formed by the operation of the vacuum-pumps, as will

40 be readily understood by all skilled in the art, the regulating-valves in the pipes f^4 and f^9 being opened and the valves f^7 for pipes f^8 and f^9 being closed. If vacuums—that is, partial vacuums—were not first formed in

45 tanks F and F' , the electrolyte would not flow from compartments B^3 and B^4 into the tanks because of the upward rush of air or liquid in tanks F and F' . When it is desired to withdraw the weakened electrolyzed solution

50 from tanks F and F' , valves f^5 and f^{10} and f' are closed and valves f^{16} and f^7 are opened, according as one may wish to regulate the

flow from tanks F and F' to the pump f^{14} through the stand-pipe f^{12} , the purposes of the stand-pipe being to make it possible to readily 70 take samples and examine and modify the recombining solutions from tanks F and F' . The pump f^{14} drives the recombining solutions to the auxiliary reservoir A^2 , where they may be further treated, if desired, and whence 75 they are fed back into the main feed-reservoir A through the conduit a^8 , provided with a regulating-valve a , or they are removed through the outlet a^{10} . The solution may be directly prepared in feed-reservoir A , but it 80 is commonly fed through a suitable pipe A^3 . A steam-pipe A^4 is provided for varying the temperature of the solution to be fed to the electrolyzing-cell.

In manufacturing on a large scale it will be 85 desirable to use the cells in series, and in the present instance I show a plurality of cells, each piped, as described, to the vacuum-mains d^{3*} and d^8 , one main being piped to the anode-containing compartments of the cells and the 90 other main being piped to the cathode-containing compartments of the cells in series.

The combination is a series of electrolytic cells constructed so as to permit of the formation of a partial vacuum over the electrolyte in each cell with a vacuum-forming apparatus common to all the anode-containing compartments of the cells and a vacuum-forming apparatus common to all the cathode-containing compartments of the cells is a very 95 valuable feature of my invention when it is to be practiced on a large commercial scale, and the combination of the cells with independent auxiliary vacuum-tanks which communicate with the stand-pipe or other devices 100 wherein the contents of the vacuum-tanks are recombined and made accessible for examination and modification and then pumped or otherwise delivered into the auxiliary feed-reservoir A^2 is another important feature of 105 my invention in its relation to large commercial practice. The cells B' are provided with suitable insulating-supports I , and these, with other insulating devices already referred to, permit the operation of the cells without any 110 unnecessary loss of electric energy. By closing valves b^7 and opening the valve b^8 a small portion of the contents of either compartment may be drawn out for examination whenever desired. In the construction shown the two 115 vacuum-tanks F and F' are connected with two cells, the tank F being common to the anode-compartments of the cells and the tank F' being common to the cathode-compartments of the cells. I may pipe additional cells 120 in series, if desired, according to the requirements of the commercial plant.

While this apparatus, as will be readily understood by all skilled in the art, may be used for the electrolysis of various electrolytes, I 130 have devised it with special reference to the electrolysis of solutions which give off a gas at each electrode during electrolysis. If, for example, it is to be desired to electrolyze ammo-

nium chlorid in solution, the same will be supplied to both compartments of the cell and chlorin gas will be generated in the anode-compartment and ammonia gas in the cathode-compartment, and these gases will be drawn off by the vacuum-forming pumps or apparatus D and D' continuously while the electrolysis is being carried on, the formation of the vacuums in the compartments permitting the rapid 5 and continuous escape of gases from the electrolyte. The construction above described permits the weakened electrolyte to be withdrawn from either one or both compartments of the cell and replaced with fresh solution 10 from the feed-reservoir A without any interruption of the process. In the case of the withdrawal of weakened ammonium-chlorid solution from the two compartments of a cell they mingle in the stand-pipe f^{12} , the flow of 15 either or both being facilitated by adjusting the valves f^{16} as the several tests of the combined solution taken from the stand-pipe f^{12} show to be necessary. Stand-pipe f^{12} is, in effect, a testing-reservoir.

20 The vacuum principle of my apparatus is of very great importance in the electrolysis of all solutions from which gaseous ions are produced, for it permits the escape of the gases from the electrolyte and lessens or prevents the diffusion of gases through the electrolyte. As is well known, the phenomena of diffusion and effusion of gases are essentially 25 different in their nature, the effusive movement affecting masses of a gas, while the diffusive movement affects only molecules, and a gas is usually carried by the former kind of impulse with a velocity many times greater than by the latter. Consequently by forming partial vacuums in such relation to the 30 electrodes that such escape is possible the electrolysis of solutions is rendered much more thorough and effective than can be possible in cases where, as heretofore, the surface of the electrolyte has been exposed in 35 whole or in part to atmospheric pressure during electrolysis.

It will be apparent that any cell may be cut out of the series of cells for repairs or renewals or cleaning without interrupting the 40 operation of the other cells or impairing their efficiency.

It is desirable in all cases, and especially when my invention is to be used in a large commercial plant, to have the feed of the 45 solution to the cell under automatic control. The solution in the series of cells should be kept practically at the normal solution-level. Where a large number of cells (from fifty to one hundred or more, for example) are to be 50 used in series, the regulation of the feed by the attendant's regulation of the feed regulators or valves a will be attended with a good deal of uncertainty, and it is desirable to avoid all uncertainty on this point by effecting the 55 requisite feed and feed-regulation without reliance on the attention of the attendants. At the same time it is desirable to retain the

regulators a^7 even when the feed is automatically controlled, for the regulators may be used to shut off the flow or as auxiliary regulators in case the automatically-operating feed-regulators fail to operate properly. The 60 automatic feed is obtained in the present form of my apparatus by the described instrumentalities; but any other automatic feed-controller may be substituted for mine.

The apparatus above described is the best form now known to me of carrying out the principle of my invention; but I do not wish to be understood as limiting myself to its details of construction, for it will be obvious that the apparatus may be constructed in a great many different forms without departure from the leading features of my invention.

In all electrolyses of saline material there is found at the electrodes at the instant of electrolytic dissociation the elementary parts of the salt used in solution, these several parts appearing at the electrodes as solid, 70 liquid, or gaseous, according to the material used. These products become diffused more or less through the electrolyte, recombining and forming secondary products, mixing with the solution and undecomposed salts, and preventing or retarding the complete dissociation of the solution, and so causing loss in results or partial failures in the ordinary methods of electrolysis that have not been overcome by any increase in the amount of 80 current or electromotive force at the electrodes.

By my present apparatus with a low electromotive force I electrolyze any desired solution and secure the most effective electrolytic result by removing immediately, continuously, and uniformly the gaseous ions from the surface of the electrodes and out of the electrolyte at the moment of their separation and away from the field of electrolytic 90 action.

One of the marked advantages of my apparatus due to the maintenance of the partial vacuums mentioned is the lessening and practical prevention of polarization. The difficulties incident to polarization are done away with, because the gaseous ions formed at and on the electrodes instantly escape into the vacuums above the electrolyte. In all 100 forms of my apparatus there is less than normal atmospheric pressure at the electrodes and on the entire surface of the electrolyte, which is out of all connection with the air. The method or process by which this important result is accomplished is a feature of my 110 invention and may be carried on by the herein-described or other forms of apparatus.

It will be observed that that cell-compartment which either contains or serves as the anode is in effect a positive receptacle, electrically considered, and that the compartment which either contains or serves as the cathode is in effect a negative receptacle, electrically considered, the electrolyte in one compartment

being in the presence of the negative electrode and the electrolyte in the other compartment being in the presence of the positive electrode. Inasmuch as electrolyzing-cells are made in a very great variety of forms and as all forms, however dissimilar in construction, comprise a receptacle wherein the electrolyte is in the presence of a cathode and also a receptacle wherein the electrolyte is in the presence of an anode, I use the phrases "positive receptacle" and "negative receptacle" to broadly indicate the known broad characteristics of electrolyzing-cells, which I have improved by the hermetically closing of each receptacle or compartment, so as to obtain vacuums therein. Hence I consider the hermetical closing of any and all kinds of electrolyzing-cells as within the scope of my present invention.

If desired, the material to be electrolyzed may be put into my hermetically-closed cells while the covers are off, and the use of the feed devices may be dispensed with, the electrolyte being in solution or in solid form, as desired, with water to be added as needed.

My hermetically-closed and vacuumized cells may be used, if desired, in fractional electrolysis, the cells communicating one with another, as will be readily understood by all skilled in the art.

In the modification shown in Fig. 5 the cover 1 hermetically closes the outer receptacle 2, which is itself the cathode. The top of the inner cylinder or receptacle 3 is hermetically closed by the dome 4. The anode-supporter 5 passes through the dome 4; but the joint is hermetically closed, and the outer portion of the supporter is of solid metal. Dotted line 6 6 represents the solution-level in the cell, and 7 and 8 are the vacuumized spaces over the electrolyte. The gas-escape pipe 7* from dome 4 leads to a vacuum-creating device 8*, and the gas-escape pipe 9 leads to a vacuum-creating device 10. Vacuum-gages 11 and reliefs 12 are provided to effectively maintain the vacuums. While the cell may be hermetically closed by any suitable mechanical means, I show a cement deposit 13 over all the joints referred to, keeping the parts of the cell in this modification as near like the corresponding parts of the old cell as is possible.

While it will be generally desirable to use a vacuum-creating device connected with each compartment, it may be occasionally preferred to use only one such device in connection with one cell, and while it will be generally desirable to provide each compartment with a gas-escape there may be cases where a gas is given off in one compartment only and the ions remain in solution in the other compartment. Hence a single gas-escape to each cell will be sufficient for some electrolyses.

In Fig. 6, showing a modification, the cover 65 of the cell is shown in place, and the electrode s is rotary, hollow, and perforated, the electrolyte being fed in through pipe s^2 . A lead

s^3 extends to the other electrode. (Shown in Fig. 7.) The purpose of perforating the electrodes is to allow the electrolyte to flow out 70 thereof into the cell.

In the modification shown in Fig. 7 electrode s is rotary and electrode s' stationary.

In the modification shown in Fig. 9 the diaphragm t separates the vacuumized spaces of 75 the cell, extending downwardly only part way from the top surface (indicated by dotted line t') of the electrolyte toward the bottom of the cell. Consequently no part of the diaphragm is between the electrodes, and the diaphragm 80 is made without porosities instead of with porosities, as in the preferred form. I have tested apparatus thus equipped and have obtained good results. I attribute the success of the tests to the rapid escape of the gases, 85 and where the nature of the electrolyte is such as to permit it a diaphragm of this construction and arrangement may be substituted for the usual diaphragm having porosities and with some advantage, as the absence of a diaphragm or partition from between the electrodes will lessen to a certain extent the internal resistance of the cell. The electrodes t^2 t^3 are supported by the leads t^3 .

In Fig. 8, which shows another modification 95 and is on a line corresponding to line 6 6 of Fig. 7, the electrode is made up of a cross-bar r , supported in brackets r' within the cell. From the bar blocks r^2 depend into the electrolyte. The construction and arrangement 100 of the electrodes may be greatly varied, as will be readily understood by all skilled in the art, the known and possible forms of electrodes being very numerous. In many other respects the apparatus forming the subject- 105 matter of the invention may be widely varied without departure from the principle of my invention.

As to the amount of vacuum which I have found practically efficient in the electrolysis 110 of ammonium chlorid, I will say that a vacuum of from five to ten inches, as shown on the vacuum-gage, gives good practical results, while a vacuum of about fifteen inches gives some better results. In my work on the electrolysis of ammonium chlorid I have not found that there is any appreciable benefit derived from a vacuum of more than fifteen inches; but in operating a large commercial plant it is probable that the degree of vacuum 120 may have to be varied.

For some uses the partition may be porous in part only, and in some cases the partition may be wholly omitted; but in all cases in apparatus working on the principle of this invention the cell is to be hermetically sealed, so that the electrolyte is out of all contact with atmospheric pressure and is not subjected directly or indirectly to atmospheric pressure. It is necessary in constructing the 125 cells containing the electrolyte to use sufficiently-strong material to withstand the atmospheric pressure, for otherwise they will be liable to be crushed.

What I claim is—

1. In electrolyzing apparatus, the combination of an electrolyzing-cell containing a diaphragm which forms two compartments within the cell; a cover for the cell; means for hermetically sealing the cover on the cell; an anode in one compartment; a cathode in the other compartment; an electrical generator electrically connected with the anode and cathode; a vacuum-creating device; a vacuum-conduit which serves as a gas-escape and is operatively connected with the vacuum-creating device and with the anode-compartment; and a vacuum-conduit which serves as a gas-escape and is operatively connected with the vacuum-creating device and with the cathode-compartment; a hermetically-sealed feed-regulator constructed and arranged to be actuated by the level of the liquid in the cell; and conduit connections from the regulator to the cell.

2. In electrolyzing apparatus, the combination of an electrolyzing-cell containing a diaphragm which forms two compartments within the cell; a cover for the cell; means for hermetically sealing the cover on the cell; an anode in one compartment; a cathode in the other compartment; an electrical generator electrically connected with the anode and cathode; a vacuum-creating device; a vacuum-conduit which serves as a gas-escape and is operatively connected with the vacuum-creating device and with the anode-compartment; and a vacuum-conduit which serves as a gas-escape and is operatively connected with the vacuum-creating device and with the cathode-compartment; a hermetically-sealed feed-regulator constructed and arranged to be actuated by the level of the liquid in the cell; and conduit connections from the regulator to the cell; a main feed or supply reservoir; and an intermediate feed-reservoir; and a conduit connection between the intermediate feed-reservoir and the regulator; the intermediate feed-reservoir having an inlet; and the main feed-reservoir having an outlet which discharges into said inlet without contact therewith.

3. In electrolyzing apparatus, the combination of a hermetically-closed, compartmental cell; a diaphragm therein; an electrode in each compartment; an electrical generator electrically connected with the electrodes; a feed-reservoir piped to the cell a

hermetically-sealed feed-regulator piped to the cell; a vacuum-creating device for and operatively connected with at least one compartment and comprising a conduit which is both a vacuum-conduit and a gas-escape conduit; a vacuum-chamber on a lower level than the cell and connected with at least one compartment of the cell, said chamber having an outlet and means for opening and controlling the same.

4. In electrolyzing apparatus, the combination of a hermetically-closed, compartmental cell; a diaphragm therein; an electrode in each compartment; an electrical generator electrically connected with the electrodes; a feed-reservoir piped to the cell; a hermetically-sealed feed-regulator piped to the cell; a vacuum-creating device for and operatively connected with at least one compartment and comprising a conduit which is both a vacuum-conduit and a gas-escape conduit; a vacuum-chamber on a lower level than the cell and connected with at least one compartment of the cell, and with the feed-reservoir; and, intermediate said vacuum-chamber and the feed-reservoir, a testing device.

5. In electrolyzing apparatus, the combination of a hermetically-closed, compartmental cell; a diaphragm therein; an electrode in each compartment; an electrical generator electrically connected with the electrodes; a feed-reservoir piped to the cell; a hermetically-sealed feed-regulator piped to the cell; a vacuum-creating device for and operatively connected with at least one compartment and comprising a conduit which is both a vacuum-conduit and a gas-escape conduit; a vacuum-chamber on a lower level than the cell and connected with at least one compartment of the cell, and with the feed-reservoir; and, intermediate said vacuum-chamber and the feed-reservoir, a testing device; and a conduit from the testing device to a feed-regulator.

In testimony whereof I have signed my name to this specification, in the presence of two subscribing witnesses, on this 8th day of January, A. D. 1898.

WILFRED BARNES.
